UNITED STATES PATENT OFFICE.

SAMUEL NEWMAN, OF CINCINNATI, OHIO.

DISPLAY OUTFIT.

No. 845,887.

Specification of Letters Patent.

Patented March 5, 1907.

Application filed May 27, 1905. Serial No. 262,578.

To all whom it may concern:

Be it known that I, SAMUEL NEWMAN, a citizen of the United States, residing at Cincinnati, Hamilton county, State of Ohio, have invented certain new and useful Improvements in Display Outfits; and I do declare the following to be a clear, full, and exact description thereof, attention being called to the accompanying drawing, with the reference characters marked thereon, which forms also a part of this specification.

This invention relates to certain improvements in the construction of devices for exhibiting wearing-apparel, clothing, garments, lingerie, either completely made up or the material therefor, the object being to exhibit such garments or the material out of which it is to be made with relation to the particular effect as to appearance when worn by a person and as to a certain material or fabric to show how it looks made up in a certain garment and worn in the intended manner.

The apparatus is constructed in a manner that the same means and devices may be used to exhibit a number of garments or patterns or colors of fabric, all of which are successively moved into view one after the other, the operation being repeated automatically.

The construction is, further, such as to permit interchange of garments and fabrics and various arrangements and combinations as to patterns, styles, or colors.

In the following specification, and particularly pointed out in the claim at the end thereof, is found a full description of my invention, together with its operation, parts, and construction, which latter is also illustrated in the accompanying drawing, in which—

Figure 1 shows a front view of my device, Fig. 2 is a side view and vertical section; and Fig. 3 is a top view thereof, partly in section. Fig. 4 shows at reduced scale a top view of a modified form of my invention.

The device consists, substantially, of an upright front A, of suitable material, which contains the open or transparent exhibiting part a and the closed non-transparent or opaque part b. The outline of the open or transparent part is shaped so that this part represents certain designs or figures to correspond to the particular object which it is desired to exhibit. Thus if material for hats merely were to be exhibited the outline sur-

rounding this open or transparent space would be arranged so that the space surrounded by it represents a hat. To show the effect and appearance of a hat made out of a certain material and when worn; a face would be shown on front A, which would be permanent for the time being at least or form a part of the non-transparent part of the front, while the material behind the open or transparent part changes from time to time. The same might be done for exhibiting shirts, waists, or vests. A permanent face would be provided on the front, while fabrics showing different colors, patterns, and materials are exhibited behind an open or transparent space below this face, such space and face being arranged with reference to each other to present a complete part of a human figure. A preferable way is to provide for a complete—that is, full—figure, as shown in Fig. 1, since such an arrangement permits simultaneous exhibit of several garments and also various changes and combinations. It further permits the limited use of any particular part of the figure to exhibit any single garment, as, before outlined. Thus, for instance, referring to Fig. 1, the lines surrounding the space a are designed to represent a human figure, such space constituting the exhibiting-space. This figure may be formed by cutting it like a stencil out of wood, sheet metal, pasteboard, or any other suitable material. The garments or fabric would be exhibited behind this cut-out space in an upright position, and by reason of the particular outline they would appear in their proper shape and relation which they later assume when made up in garments and worn by a person. This exhibiting-space may be left open or be closed by glass or other transparent material. If to be closed by glass, the entire front A may be made of a pane of glass, the parts which surround the exhibiting-space being rendered non-transparent by being covered with paint or otherwise. Such parts as the face, hands, shoes, buttons, &c., would of course be also permanent, appearing within the space supported in a suitable manner—as, for instance, when such space is closed by transparent glass they would be painted upon such glass or indicated in lines thereon. This may also be done with reference to such parts of which no exhibits are to be made, as of hats and trousers. The exhibits behind such space would be supported

in suitable numbers on upright carriers B, which move so as to show one exhibit after the other behind the exhibiting-space.

The movement is in a horizontal direction, which permits a convenient arrangement of the exhibits. Thus, for instance, the design as shown in Fig. 1 may be used to exhibit simultaneously material for trousers, shirts, vests, coats, hats, &c., such material being placed in horizontally-arranged strips on the upright carriers. These latter may consist of a backing of suitable material like canvas, stretched in form of an endless belt around and over a number of rollers, which are moved, or, as shown in Figs. 2 and 3, this carrier is supported on upright rods C, the ends of which are attached and supported between sprocket-chains D, stretched around and moved by sprocket-wheels E, which are mounted on upright shafts F. One of these latter is positively rotated in any suitable manner—as, for instance, by a set of bevel-wheels G—being driven by a suitable motor or mechanism H. The carrier B or the exhibits might also be supported to form the

side of a prism or cylinder supported on a central shaft L, as shown in Fig. 4.

Having described my invention, I claim as new—

In a display device, the combination of an upright front containing an exhibiting-space through which fabric supported back of it may be seen, the outline of this exhibiting-space being arranged to represent a human figure, an endless carrier upon which this fabric is held, upright rods around which this endless carrier is passed and whereby it is sustained in upright position, two endless sprocket-chains between which these rods are carried, sprocket-wheels around which these chains pass each in a horizontal plane and one below the other, upright shafts upon which these sprocket-wheels are mounted and means to rotate one of these shafts.

In testimony whereof I hereunto affix my signature in the presence of two witnesses.

SAMUEL NEWMAN.
